UNITED STATES PATENT OFFICE

ANGELO CARLESIMO, OF DETROIT, MICHIGAN

BUCKET CLEANER FOR EXCAVATING MACHINES

Application filed September 17, 1928. Serial No. 306,329.

This invention relates to trenching or excavating machines, but more particularly to cleaners for removing dirt, etc. from the buckets of such machines.

5 Objects of this invention are to provide a simple and efficient bucket cleaner which is yieldingly held by gravity in cleaning position, but is capable of limited movement away from cleaning position; to provide a 10 bucket cleaner which has a frangible or breakable element adapted to give way in the event a pressure in excess of a predetermined maximum is exerted in order to prevent injury to the working parts of the machine; and to 15 provide a bucket cleaner having the new and improved features of construction and arrangement hereinafter described.

The invention is shown by way of illustration in the accompanying drawings, in 20 which:

Fig. 1 is a sectional elevation on the line 1—1 of Fig. 2, showing the outer end of a digging beam with a bucket cleaner installed thereon and in raised position; and

25 Fig. 2 is a top plan view of the outer or cleaning end of the bucket cleaner.

The illustrated embodiment of the invention comprises a digging beam 1 of an excavating or trenching machine, only the outer 30 end portion thereof being shown. Fixed to the outer end of the beam 1 is a bracket 2 providing a bearing for a horizontally disposed sprocket wheel shaft 3, a sprocket wheel 4 being mounted on the shaft 3. Trained about the sprocket wheel 4 is a chain 5, to which a series of digging and conveying buckets 6 are secured, only one of such buckets being shown. It is to be understood that a second 35 sprocket wheel is mounted in spaced relation on the shaft 3, and a chain is trained over this wheel to provide a support for the opposite sides of the buckets. It will be readily understood that the sprocket wheel 4 is rotated in counter clockwise direction, and as 40 the buckets pass about the sprocket wheel, their contents are discharged.

In order to clean or scrape the material, such as dirt, stones, etc., from the buckets as they pass around the sprocket wheel, a 45 cleaner unit C is mounted adjacent the outer

end of the beam. The inner end of the cleaner unit C is pivotally connected at 7 to the bracket 2, and consists of a relatively long arm 8 and a short arm 9, which are pivotally connected at 10. It is apparent that the 55 cleaner unit is so mounted that the free or outer end drops down by gravity to the position shown by the dotted lines, a stop 11 on the bracket 2 limiting the downward movement of the cleaner. When the cleaner is in 60 position resting upon the stop 11, it is properly positioned for cleaning, and the outer end of the cleaner passes through the buckets as they travel around the sprocket wheel 4.

In the event that the outer end of the 65 cleaner encounters a resistance sufficient to overcome its inertia, it may be moved upwardly about its pivot 7 into engagement with a stop 12 on the bracket 2 above the stop 11, and as soon as the pressure is relieved, the cleaner drops back by gravity to 70 its normal cleaning position. It is, therefore, manifest that the cleaner C has limited movement between the stops 11 and 12, and may be swung in a vertical direction about its 75 horizontal pivot 7 away from cleaning position.

As shown in Fig. 2, the short arm 9 of the cleaner C is somewhat wider than the arm 8, and a relatively long cleaning blade 13 is 80 detachably connected to the arm 9 by a series of bolts and nuts 14. The blade 13 may be of sufficient length to cover substantially the bottom of the buckets 7 in order effectively to remove all material therefrom.

The arm 9 is provided with a rearward central extension 15, and the arm 8 is provided with a pair of outwardly extending brackets 16, between which the extension 15 is disposed. The brackets 16 and extension 15 are 90 formed with registering openings to receive a shear pin 17.

Normally upon engagement of the material in the buckets 6 with the cleaner unit C, the outer or free end is swung upwardly 95 until the stop 12 is encountered. Continued travel of the buckets 6 causes the material to be scraped therefrom and thereafter the cleaner unit drops downwardly against the stop 11. It is apparent that should muck or 100

other sticky substance adhere to the cleaning blade 13, the shock of impact occasioned by the cleaner unit C striking the stop 11 in its downward movement will tend to jar such material loose to present a relatively clean blade for the next succeeding bucket.

Should a shock be imparted to the cleaner C which not only raises it into engagement with the stop 12, but this is insufficient to relieve the pressure on the outer end portion of the cleaner, the arm 9 may be swung about its pivot 10 in a clockwise direction, the pin 17 being first sheared to permit this movement. This will take place should the movement of the cleaner between the stops 11 and 12 be insufficient to relieve the pressure against the end portion of the cleaner, the strength of the shear pin 17 being so chosen that the same will be sheared in the event that the pressure or shock imparted to the cleaner is in excess of a predetermined maximum.

It is apparent that with this construction, the bucket cleaner is normally held by gravity in cleaning position, and is allowed a limited movement between the stops 11 and 12 to relieve the pressure thereagainst sufficient to overcome its inertia. In order to prevent injury to the working parts of the machine in case an unusually great shock or pressure is imparted to the end portion of the cleaner, the shear pin 17 is severed, thereby permitting the arms 9 to swing in a counter clockwise direction. Thereafter to render the cleaner effective, it is necessary simply to replace the pin 17.

Numerous changes in details of construction and arrangement may be effected without departing from the spirit of the invention, especially as defined in the appended claims.

What I claim as new and desire to secure by Letters Patent is:

1. In a trenching machine having a series of digging and conveying buckets and a wheel about which said buckets travel, a bucket cleaner having an end pivotally mounted and the opposite end provided with a cleaning blade, the weight of such outer end being sufficient normally to hold said cleaner in cleaning position said cleaner comprising a pair of pivotally connected arms, one arm being pivoted intermediate its ends to the other arm, and a shear pin connecting the inner end of the former arm to the latter arm, thereby to permit relative movement of said arms when a pressure is exerted thereagainst in excess of a predetermined maximum.

2. In a trenching machine having a digging beam, a sprocket wheel at the outer end thereof, a series of digging and conveying buckets adapted to travel about said sprocket wheel, a bracket, a cleaner pivoted at one

end to said bracket, the opposite end of said cleaner being held downwardly in cleaning position by gravity, a stop on said bracket limiting the downward movement of said cleaner, another stop on said bracket limiting the upward movement of said cleaner, said cleaner comprising a long and short arm pivoted together, said short arm being pivoted intermediate its ends to the long arm, and a shear pin connecting the inner end of said short arm to said long arm thereby to permit relative movement of said arms when a shock in excess of a predetermined maximum is encountered.

3. In an excavator bucket cleaner, an arm, means to movably mount the arm at one end thereof for bodily swinging movement, and for causing the arm to respond to the action of gravity, a stop above the arm and a stop spaced from the first stop and located below the arm for limiting movements thereof, and a cleaner carried by the opposite end of the arm, and being held in operative position by the force of gravity.

4. In an excavator bucket cleaner, an arm, means to movably mount the arm at one end thereof for swinging movement, and for causing the arm to respond to the action of gravity, a stop above the arm and a stop below the arm for limiting movements thereof, a cleaner pivoted to the outer end of the arm, and means for normally holding the cleaner against pivotal movement relative to the arm and for enabling same to have pivotal movement when the cleaner is subjected to an injurious force.

5. In an excavator bucket cleaner, a cleaner carrier, means to movably mount the carrier for causing same to bodily respond to the action of gravity, spaced stop means spaced from each other and disposed on opposite sides of the carrier to engage same and restrict gravitational and upward movement of the carrier, and a cleaner on the carrier, and held in operative position by the force of gravity.

6. In an excavator bucket cleaner, a cleaner carrier, means to movably mount the carrier for causing same to respond to the action of gravity, spaced stop means on opposite sides of the carrier to engage same and restrict gravitational and upward movement of the carrier, a cleaner pivoted to the carrier, and releasable means for normally holding the cleaner against pivotal movement relative to the carrier and for enabling same to have pivotal movement when the cleaner is subjected to an injurious force.

7. In an excavator bucket cleaner, an arm, means to movably mount the arm at one end thereof for bodily swinging movement, and for causing the arm to respond to the action of gravity, means to positively limit upward and means spaced from the last named means

to limit downward movement of the arm, and a cleaner carried by the opposite end of the arm, and held in operative position by the force of gravity.

5 In testimony whereof I have hereunto signed my name to this specification.

ANGELO CARLESIMO.
